UNITED STATES PATENT OFFICE.

WILLIAM THOMAS SPILANE, OF CROOKSTON, MINNESOTA.

RAILROAD SAFETY APPLIANCE.

1,426,922.

Specification of Letters Patent. Patented Aug. 22, 1922.

Application filed July 15, 1921. Serial No. 424,888.

To all whom it may concern:

Be it known that WILLIAM THOMAS SPILANE, a citizen of the United States of America, residing at Crookston, in the county of Polk and State of Minnesota, has invented new and useful Improvements in Railroad Safety Appliances, of which the following is a specification.

The object of the invention is to provide a simple and efficient means for automatically applying brakes to a railway train or car in the event that the siding switch is left open or a semaphore signal is set against the train and is not observed by the engineer or the proper steps are not taken by him to check the progress of the train; and with this object in view the invention consists in the construction, combination and relation of parts of which a preferred embodiment is shown in the accompanying drawings, wherein:

Figure 1 is an end view of a car equipped with a safety appliance embodying the invention and showing in connection therewith a switch stand and a semaphore signal both arranged in positions indicating danger.

Figure 2 is a plan view of the same, the roof of the car being broken away to show the relation of the parts of the safety appliance.

Figure 3 is a longitudinal sectional view of the same.

Figure 4 is a detail view of the connecting rod and crank shaft showing the relation thereof to the means for reducing the train pipe pressure.

The apparatus consists essentially of a crank shaft 10 having arms 11 which extend upward at opposite sides of the car 12 in position to be engaged by trip arms 13 and 14 which are respectively carried by or connected with a switch stand 15 and a semaphore arm 16. Obviously there are numerous ways in which these trip arms may be mounted and carried under such conditions as to be interposed in or arranged in intersecting or engaging relation with the arms 11 on the car apparatus when the switch which is controlled by the switch stand or the semaphore arm 16 is in the danger position so as to cause the operation of the crank shaft, and therefore the arrangements illustrated in the drawing may be regarded merely as typical and are so simple as to indicate that unless the switch stand

and the semaphore signal are in positions indicating safety or a clear track ahead the trip arms thereof will be interposed or arranged in obstructing relation with the operating arms of the car mechanism to cause an actuation of the crank shaft.

In the illustrated arrangements of these trip arms the element used in connection with the switch stand is attached to the switch target 17 in such a relation thereto as to be disposed in operative position when the switch is open while the trip arm 14 for the semaphore may as illustrated be mounted upon a standard 18 counterweight 76 and 19 and connected by a rod 20 or its equivalent with the semaphore arm 16.

Between the crank 21 of the crank shaft and a crank arm 22 attached to a valve stem 23 is arranged a connecting rod 24 adapted 78 when the crank shaft is turned in either direction by the swinging of either of the arms 11 either forward or backward, according to the direction of movement of the car, to turn the valve stem which controls 80 a valve in the valve casing 25 for opening an exhaust from the train pipe branch 26 forming an element of the airbrake mechanism which obviously may be of any preferred construction and a specific illustration of which is unnecessary in this connection. Said branch is preferably provided

with a cut-off valve 27 by which the safety mechanism may be eliminated when desired. Also the crank arm 22 may be connected 80 by a rod, wire or equivalent means indicated at 28 with an alarm mechanism 29 preferably of the audible type such as a bell or whistle.

In order to avoid interference between the car carried element of the safety appliance and the trip arms which form parts of the roadside mechanism the operating arms 11 are of yielding construction tending to expand or swing outward toward their free ends and are arranged in arcuate or bowed guides 30 so that when said arms are in their normal or neutral upright positions they incline outwardly toward the sides of the road in position to be engaged by trip arms which terminate short of the planes of the sides of the car, and as said operating arms are swung toward their folded positions by contact with the trip arms they are moved inward by the curvature of the guides 30.

Also in connection with the connecting

rod 24, as a means of holding the crank shaft in its normal or neutral position and of yieldingly locking said shaft in one or the other of the adjusted positions when one of the operating arms has been engaged and deflected by a trip arm, there is employed a spring arm 31, preferably of looped form carrying a grooved roller 32 for traversing the connecting rod, and the latter is provided with an offset 33 forming cam surfaces 34 to be traversed by said roller. When the roller is at the bottom of the offset formed by the intersection of the cam surfaces the rock shaft is held in position to maintain the operating arms in their upright position for engagement by the trip arms and when the rock shaft is turned by contact of a trip arm with one of the operating arms the movement of the connecting rod through a short distance in either direction causes the spring arm to exert a force tending to throw the crank arm to the limit of its movement in the direction in which it has been started and to then hold the crank shaft in the adjusted position with the relief valve of the train pipe open to reduce the pressure therein and hence apply the brakes for the purpose of checking the progress of or stopping the train or car. It will be obvious that the car equipment is of relatively simple construction involving but a small cost in the matter of installation and maintenance and that the roadside mechanism being dependent upon the switch and signal devices already in use can be installed without modifying the apparatus already used in this connection.

Having described the invention, what is claimed as new and useful is:—

1. A railway safety appliance comprising car body carried operating arms mounted for swinging movement in planes parallel with the path of the car and adapted for contact with and to be operated by a roadside trip, a crank shaft at the extremities of which said arms are carried, a connecting rod connected to the crank of said crank shaft and having an offset providing oppositely inclined cam faces, a spring arm having transverse bearing engagement with the offset for yieldingly holding the connecting rod and crank shaft with the operating arms in their normal position, and operative connections between said connecting rod and the air brake mechanism for effecting a reduction of train pipe pressure.

2. A railway safety appliance comprising car carried operating arms mounted for swinging movement in planes parallel with the path of the car, a crank shaft disposed transversely in the car and carrying the operating arms at opposite ends thereof, connections between said crank shaft and the air brake mechanism for effecting a reduction of train pipe pressure, said operating arms being laterally yieldable with relation to the path of movement of the car, and arcuate guides straddling the arms for controlling the lateral swinging movement of the same.

In testimony whereof he affixes his signature.

WILLIAM THOMAS SPILLANE.
